SIGN CONSTRUCTION

Luke W. Joyce, River Rouge, Mich.

Application October 24, 1938, Serial No. 236,630

2 Claims. (Cl. 40—145)

My invention relates to a new and useful improvement in a sign construction adapted for use as a street indicating sign and the like.

It is an object of the present invention to provide a sign mountable on a standard and so constructed and arranged as to be durable, economical of manufacture, easily and quickly installed and highly efficient in use.

Another object of the invention is the provision of a sign so arranged and constructed that the indicia bearing faces will be visible and free from any shielding effect of the other parts.

Other objects will appear hereinafter.

The invention consists in the combination and arrangement of parts hereinafter described and claimed.

The invention will be best understood by a reference to the accompanying drawing which forms a part of this specification, and in which,

20 Fig. 1 is a perspective view of the invention with a part of the standard broken away.

Fig. 2 is a fragmentary side elevational view of the invention with a part broken away and a part shown in section.

25 Fig. 3 is a view similar to Fig. 2 taken at right angles thereto.

Fig. 4 is an end elevational fragmentary view of a slightly modified form.

As shown in the drawing the sign is used with a standard or post 9 which is firmly mounted at the desired location. This post is indicated as tubular and provided on its upper end with a threaded portion. Threaded on this threaded portion is a cap 10 secured in position by the set screw 11. This cap 10 carries the sign boards 13 and 16 in the form shown I have indicated a pair of these boards extended at right angles to each other. The cap 10 is provided with a diametrically extending slot 12 in which the lower edge of the sign board 13 is positioned, this slot extending down the side walls of the cap 10 so that the inner edge of the sign board 13 will be positioned below the inner surface of the cap 10. This plate 13 is then welded in position, the weld 14 accumulating the opposite sides of the edge of the board 13 on the inner surface of the cap 10.

50 Welded on the upper edge of the sign board 13 is a rectangular plate 15, the board 13 extending diagonally thereof. Resting upon this securing plate 15 is a sign board 16 which is welded thereto and extends diagonally thereof so that the sign boards 13 and 16 extend substantially at right angles to each other. This, of course, is the desired mounting if the sign boards are used to indicate a pair of intersecting streets extending at right angles to each other. The angularity of

these boards 13 and 16 may, of course, be changed to meet the conditions peculiar to the use to which the sign boards are to be a part.

Thus, the cap and the sign boards 13 and 16 and the securing board 15 are bonded together 5 into a unitary whole and after the post is mounted in position, this unitary structure may be easily and quickly mounted on top of the post and the screw 11 driven home to prevent the structure from being unduly removed from the post. 10

In Fig. 4 I have shown the cap 10' provided with a threaded stud 17 projecting therefrom and threading into a socket 18 formed in the upper end of the post 9' so that, if desired, a solid post may be used and the invention embodied there- 15 with.

It is believed obvious that a compact, durable and economically manufactured structure is thus provided and that a well-appearing street sign is thus afforded. 20

While I have illustrated and described the preferred form of construction, I do not wish to limit myself to the precise details of structure shown, but desire to avail myself of such variations and modifications as may come within the scope of the 25 appended claims.

What I claim as new is:

1. A sign construction of the class described, comprising: a supporting post having a threaded portion on its upper end; a cup-shaped cap 30 threadable on said upper end, said cap having a diametrically extending slot formed through its base and extending into its side walls; a sign board positioned in said slot and projecting beyond the inner face of the base of said cup-shaped cap and welded thereto; a securing plate mounted on the upper edge of said sign board; and an additional sign board resting upon the upper face of said securing plate and secured thereto and extending angularly to said first-mentioned sign 35 board. 40

2. A sign construction of the class described comprising: a supporting post; a cup-shaped cap mounted on the open end of said post, said cap having a diametrically extending slot formed 45 through its base and extending into its side walls; a sign board positioned in said slot projecting beyond the inner face of the base of said cup-shaped cap and welded thereto, there being a weld on the inner face and the outer face of said base of said cap; a securing plate mounted on the upper edge of said sign board; and an additional sign board resting upon the upper face of said securing plate and secured thereto and extending angularly to 50 said first-mentioned sign board. 55
